UNITED STATES PATENT OFFICE.

WILLIAM T. VAN DORN, OF CHICAGO, ILLINOIS.

CAR END.

1,070,380.

Specification of Letters Patent. Patented Aug. 12, 1913.

Application filed March 24, 1913. Serial No. 756,373.

To all whom it may concern:

Be it known that I, WILLIAM T. VAN DORN, a citizen of the United States, and a resident of the city of Chicago, in the county 5 of Cook and State of Illinois, have invented certain new and useful Improvements in Car Ends; and I do hereby declare that the following is a full, clear, and exact description of the same, reference being had to the 10 accompanying drawings, and to the numbers of reference marked thereon, which form a part of this specification.

This invention relates to a car end construction which may be attached to an ordinary 15 wooden freight car either during the course of repair of the same, or when the same is constructed or first assembled.

The light wooden ends heretofore forming the end walls of the usual type of wooden 20 freight car have proved inadequate for the purpose and slight damage thereto may seriously affect the contents of the car. Such ordinary types of wooden car ends are of insufficient strength to withstand the stresses 25 imposed thereupon by the almost continuous buffing to which the car is subjected. Under usual conditions, the side walls of the car are subjected to only a comparatively small amount of stress by the contents within 30 in the car when the car is set in motion or brought to a stop, while on the other hand, the car ends receive the full effect of the inertia of the contents of the car.

The side walls of the car are very seldom 35 contacted by other objects, while the car ends are often battered and injured, during the transfer of the car, and hence it becomes necessary to provide a car end capable of withstanding the enormous stresses imposed thereon and acting at all times to remain closely attached to the corner posts or side walls of the car to prevent a leakage of the contents therefrom.

It is an object of this invention to provide 40 a pressed metallic car end adapted to be attached to an already completed car or forming an element of a car under the course of construction.

It is also an object of this invention to 45 provide a suitably pressed metallic car end capable of distortion in case of accident thereto without parting from the car along its edges or line of attachment.

It is also an object of this invention to 50 provide a sectional reinforced metallic car

end which will permit replacement of any one of said sections when desired.

It is also an object of this invention to provide a corrugated car end affording a plurality of continuous or unending corrugations extending longitudinally and transversely of the car end.

It is also an object of this invention to provide a car end attached to the corner posts, the end plate and the end sill of the 65 car, as well as to the intermediate car posts between the ends.

It is also an object of this invention to provide a plurality of metallic car end sections adapted to be secured together and 70 mounted on the car, either horizontally or perpendicularly.

It is also an object of this invention to provide a reinforced metallic car end consisting of a plurality of sections having concentric corrugations thereon.

It is also an object of this invention to provide reinforced metallic car ends suitably attached to the ends of a car, and wherein said car ends are connected together 80 and retained from displacement by the truss rods of the car.

It is furthermore an object of this invention to provide substantially constructed metallic car ends attached to the corner and 85 intermediate posts of a car frame and affording a brace for the side walls and top thereof.

It is finally an object of this invention to provide a substantial and practically invulnerable car end construction of extreme simplicity and relatively light weight.

The invention (in a preferred form) is hereinafter more fully described and defined in the appended claims.

In the drawings: Figure 1 is a front elevation of a car end embodying the principles of my invention. Fig. 2 is a longitudinal section taken through the car on line 2-2 of Fig. 1. Fig. 3 is a fragmentary section showing the interior of the car end and taken on line 3-3 of Fig. 2. Fig. 4 is an enlarged fragmentary section taken on line 4-4 of Fig. 3, showing in detail the attachment of a metallic car end to a car frame. 105 Fig. 5 is a fragmentary transverse section taken on line 5-5 of Fig. 1. Fig. 6 is a front elevation of a car end section adapted to a gondola car. Figs. 7 and 8 are enlarged sectional details showing means of 110

connecting a car end along its bottom to the buffer block of a car. Fig. 9 is an enlarged sectional detail illustrating the car end retained between the end sill and buffering block and clamped therein by the truss rods of the car.

As shown in the drawings: the reference numeral 1, indicates an upper section and 2, a lower section of a car end embodying my invention. As shown, said sections are suitably connected together along a riveted seam 3, although it is obvious that any other suitable connection may be effected therebetween to suit the purpose. The lower edge 5 of section 2, is secured to a buffering block 4, by means of an angle iron 5, said buffering or dead block being shown as extending entirely across the car, adjacent to and of substantially the same length as the end sill 6. The section 1, is secured along its upper edge 10 to an end plate member 7, said edge being covered on the outside of the car by the end fascia board 8. The side margins of said sections 1, and 2, are flanged over, as shown 15 at 9, for attachment to corner posts 10, of the car frame. Means are also provided for reinforcing the car frame as a whole, as well as serving to retain the metallic corrugated sections in fixed relation upon the corner 20 posts of the car frame. Such means comprise tie rods 11, which extend through the corner posts and metallic end sections, and are tightly secured on the outside of the latter by means of nuts and washers. Said tie 25 rods 11, extend longitudinally of the car and may be secured upon any of the intermediate posts 12.

Suitable sway bracing members 13, extend diagonally between the car posts to reinforce the same against the tension of the tie rods 11. Longitudinal tie rods 14, are shown extending from one end of the car to the other, and are secured upon the outer surface of the metallic end sections by nuts and washers similar, to the rods 11. The lower section of the metallic car end may be 30 likewise connected together by means of the truss rods 15, which, as shown in Figs. 4 and 9, extend through the end sill 6, and the dead block 4, and also through the extended edge of the section 2, which is thereby secured between the members 4 and 7.

Fig. 6 illustrates a single end section 2, affording the end of a gondola car. The lower edge thereof may be secured to a car in any suitable manner and for convenience is shown as attached to the dead block 4 of the car frame by means of an angle iron 5. The upper edge of said section 2, is attached 40 to the car framing by means of a similar angle iron 5a.

Fig. 8 illustrates a modification of the means for attaching the lower edge of the section 2, to the car frame and consists in flanging said lower edge outwardly at a

substantially right angle and attaching the same by means of bolts to the dead block 4.

The operation is as follows: As already pointed out, it is desirable to have a car end of great strength and one capable of distortion without parting from the car frame along the attaching edges, and accordingly a car end made up of sections 1 and 2, although more may be used if desired, are shown as concentrically corrugated over practically the entire area thereof. By so disposing the corrugations, corrugations running in all directions on the plate are thereby afforded so that the force tending to distort the car end will be distributed over a large portion of the attaching edge and not applied at any point thereof, a result which would effect a consequent tearing away of the edge at such a point. By using the continuous straight and curved corrugations, I thereby secure an area which includes horizontal and vertical, or in other words, transverse and longitudinal lines of corrugations, as well as corrugations directed at all angles therebetween.

It is entirely feasible to construct the car ends of more than two sections, and in such event the straight portions of the continuous corrugations would be foreshortened and to such an extent, if desired, to omit the straight portions of the corrugations and thereby form a section of bull's-eye form, as shown in my Patent #835,170, issued on November 6th, 1906. It is also clear that my invention may be adapted to any type of car as, for instance, an all steel car, although for convenience of illustration I have shown the same merely associated with an ordinary gondola and box-car.

I am aware that details of construction may be varied to a wide range without departing from the principles of this invention, and I therefore do not purpose limiting the patent granted otherwise than necessitated by the prior art.

I claim as my invention:

1. The combination with an end sill and corner post of a railway box car, of a metal end comprising upper and lower plate sections, said sections being formed with continuous straight and curved corrugations.

2. The combination with an end sill and corner post of a railway car, of a metal end comprising a plurality of sections, said sections secured together and to the corner post and end sill of the car, and connected straight and curved corrugations formed in said sections to reinforce the same.

3. The combination with the frame of a railway car, of a metal end comprising a plurality of sections secured together and to said car frame, and parallel and concentric corrugations formed in said sections.

4. The combination with a railway car frame, of a metal end comprising a plurality

of concentrically corrugated sections, said sections flanged at the edges to engage over the front and sides of the corner post of the car frame.

5. The combination with an end sill, corner post and roof structure of a railway car, of a metal end comprising a plurality of corrugated sections secured together, the corrugations thereof continuous, connected, and parallel, one of said sections secured to the end plate of the roof structure, another of said sections secured to the end sill, and the side edges of the outer section flanged over to engage around the face and side of said corner post.

10. The combination with an extended dead block and corner post of a railway car, of a metal end comprising a plurality of sections secured to said dead block and corner post, and being formed with a plurality of concentric corrugations.

15. The combination with a railway car frame, of a metallic end comprising a plurality of sections, said sections secured together and having continuous connected and parallel corrugations formed thereon, and tie rods extending from said metal ends to intermediate posts in the car frame to transmit the stresses imposed on the car end section to a portion of the car frame other than the corner post and end sill thereof.

20. The combination with a railway car frame, of a metal end comprising a plurality of concentrically corrugated sections, one of said sections flanged downwardly over the end sill of the car adapting the truss rod thereof to extend therethrough and clamp the same thereon.

25. The combination with the end sill, truss rod and corner post of a railway car, of a metal end comprising a plurality of straight and curved continuous corrugated sections, flanges thereon extending around and attached to the corner post of the car frame, and a flange extending over the end sill and apertured to receive the truss rod thereto to secure said metal end thereon.

30. The combination with an end sill and corner post and end plate of a railway car, of a metal end comprising a plurality of continuously corrugated sections, the corrugations thereof connected to one another, flanges on said metal ends for attachment to said end plate, end sill, and corner post.

35. 11. In a device of the class described a metallic car end comprising a plurality of

concentrically corrugated sections, and angled flanges on the sides and ends thereof adapted for attachment to the corner post and dead block respectively.

60

12. In a device of the class described a sectional concentrically corrugated metallic car end, and means securing the same on a car frame to other than the end members thereof.

65

13. In a device of the class described a metallic car end, continuous connected corrugations thereon, and means on said car end for attachment to a car frame adapting the truss rods thereof to secure the respective ends on the car frame and fasten the same together.

70

14. In a device of the class described a sectional metallic car end, continuous corrugations thereon, and the side of said end flanged at the substantially right angle for attachment on the outer surface of an end post of a car frame.

75

15. In a device of the class described a sectional metallic car end, a plurality of concentric and parallel corrugations formed on the surface thereof, and means attaching said end to the corner post and end sill of a car frame.

80

16. In a device of the class described a sectional metallic car end, each of said sections having a plurality of connected transverse and longitudinal corrugations therein.

85

17. In a device of the class described a sectional metallic car end, and continuous connected straight and curved corrugations thereon.

90

18. In a device of the class described a sectional metallic car end, straight and curved corrugations thereon, means securing said ends to the end posts of a car frame, and means securing said ends to the intermediate posts of a car frame.

95

19. In a device of the class described a sectional metallic car end, a series of unending corrugations thereon, means formed on said sections affording attachment thereof to the end members of a car frame, and means connecting said sections with intermediate members of the car frame.
